UNITED STATES PATENT OFFICE.

HENRY W. SCHLOSS, OF NEW YORK, N. Y.

DESIGN FOR DRESS-TRIMMING.

SPECIFICATION forming part of Design No. 21,794, dated August 23, 1892.

Application filed April 28, 1892. Serial No. 431,080. Term of patent 8½ years.

To all whom it may concern:

Be it known that I, HENRY W. SCHLOSS, a citizen of the United States, residing in New York, in the county of New York and State 5 of New York, have invented a new and original Design for Dress-Trimming, of which the following is a specification.

My design is fully shown in the accompanying drawing, which represents a face view of 10 a piece of the trimming.

The new and original design consists of a band or base-strip *a*, from which hang a series of ribbons. These ribbons as heretofore designed have been plain, like close woven ribbon or braid of the ordinary nature.

15 The leading feature of my design is the ribbons *b*, having holes *b'* regularly placed in

diagonal lines, so that they have the ornamental appearance of ribbons or bands of lace or grenadine. Above the base-strip to which 20 the ribbons are connected is an edging formed of a succession of rectangular points.

I claim—

The design for dress-trimming, substantially as described, and as shown in the accompanying drawing.

In witness whereof I have hereunto signed my name in the presence of two subscribing witnesses.

HENRY W. SCHLOSS.

Witnesses:

JAMES F. KAVANAGH,
FRANK S. OBER.
